EUSTACHIUS W. KOERING, OF VINELAND, NEW JERSEY

TOWEL BAR

Application filed August 24, 1926. Serial No. 131,170.

This invention relates to a towel bar or similar object and more particularly to such a bar composed of glass or other vitreous material and a novel means for supporting the same from a wall or other surface.

It has been the common practice heretofore, in towel bar construction to employ all metal construction or where such materials as glass, porcelain or wood are used, to employ a straight rod of the required length and support the same by brackets extending outwardly from the wall at right angles to the bar. Metal bars are objectionable since the metal readily tarnishes in contact with damp towels, etc., and such bars are not acceptable in modern home construction. The vitreous or enameled wooden bars are more substantial in appearance but it is difficult to firmly secure such bars in the outwardly extending brackets so that they do not rapidly loosen therein and thus become a source of annoyance, due to rattling, entrance of dirt into the bracket opening adjacent the ends of the bar and in the case of metal brackets, corrosion of the metal renders them unsightly.

The trend of present day construction for bath rooms, lavatories, kitchens, etc., is in the employment of tiled walls with "built-in" fixtures of a nature in keeping with the tile construction. In a copending application, Serial No. 754,705, filed Dec. 9, 1924, entitled Towel bar, I have disclosed a novel towel bar composed of glass, porcelain or other vitreous, noncorrodible and easily cleaned material, having a substantial portion adjacent each end bent inwardly at right angles to the body portion to offset the bar from the wall, each of the inwardly turned ends being supported by a bracket of metal or other suitable material secured to the wall by screws or equivalent fastening means. Such form of bar has found favor in construction in which tile is not utilized but in the form shown in the aforesaid application is not well adapted for tiled-wall construction.

One of the objects of the present invention is therefore, to provide an improved vitreous bar and supporting means therefor, which is suitable for use in tile construction and which may be applied either to existing construction

or incorporated in the wall at the time it is made.

Another object is to provide a towel bar which is composed entirely of vitreous material having no metal parts and in which the usual bracket posts are dispensed with.

Another object is to provide a towel bar which is simple in construction, pleasing in appearance and which is in keeping with the highest class of present day bath room construction.

Other objects and advantages will herein-after appear.

In accordance with the present invention I provide a bar of glass or other vitreous material having its ends bent inwardly and secured directly to the wall by any suitable means as by cement. A ring flange of material similar to the bar is employed about the ends of the bar where they enter the wall for the purpose of enhancing the appearance of the bar and to protect the cement from moisture. A shoulder, flange or other form of abutment is formed on each end of the bar for engagement against the ring flange to prevent displacement of the ring flange along the bar and to close the opening in the ring flange against entrance of dirt and water.

A modified construction contemplates the use of a special tile having a recess in which the end of the bar is cemented. The ring flange may be formed separately from the tile or integral therewith. If formed integral therewith, the rod or bar does not need to be provided with the shoulder or abutment, although I prefer to employ the same both for the sake of appearance and to completely close the opening in the ring flange. Instead of cementing the bar in the tile, a metal retaining member may be used.

In order that the invention may be more fully understood reference will be had to the accompanying drawing in which,

Fig. 1 is an elevation partly in section of the towel bar, embodying my invention, applied to a wall.

Fig. 2 is a modified arrangement of the supporting means employing a special form of tile.

Fig. 3 is a still further modification utilizing a special form of tile, and

Fig. 4 is another modification showing in section the manner of securing the bar in the wall and covering the wall connection.

5 The embodiment of the invention shown in Figure 1, comprises a bar 1 of glass or other vitreous material, having inwardly turned ends 2 and 3 secured in the wall 4. The wall 4 is shown as of tile construction and consists 10 of tiles 5 cemented to plaster 6. A recess 7 in the wall is provided for the ends 8 of the bar in which they are rigidly secured, as by cement 9. To assist in bonding the bar to the 15 cement, the ends 8 may be roughened in any desired manner, as by sand blasting, acid etching, etc., or by forming corrugations, as shown in Figure 1, or other form of irregularities therein.

20 In order to protect the cement 9 from dirt and water and to cover the cemented joint from sight, a ring flange 10 of glass or tile having an opening 10' may be provided therefor. The ring flange is held tightly against 25 the tile 5 by an abutment on the bar which may take the shape of an annular bead 11. The bead 11 also closes the opening 10' in the ring flange and prevents the entrance of dirt and water therein.

30 In Figure 2 I have shown the bar secured directly to the tile 12 alone. In this form the ring flange 13 is formed integral with the tile. In place of cementing the bar in the tile I have shown a metal retaining member 14 in 35 the form of a thin concave annulus having its inner periphery formed with a plurality of spring fingers 15 engaging in a circumferential groove 16 in the end of the glass bar. The inner portion of the retaining disc is reversely 40 bent so as to project the fingers 15 normally in an inwardly and axial direction so that rigidity is imparted thereto both in an axial and radial direction and to permit the disc to be snapped over the end of the glass bar and to 45 firmly grip the same in a resilient manner. The outer edge of the retaining disc engages in a recess 16' in the back side of the tile so as to exert a longitudinal force on the bar to restrain it from longitudinal movement in the 50 tile and maintain the bead 11 in contact with the face of the tile.

Figure 3 shows another form of tile provided with a recess 17 in which the roughened end of the bar is cemented. In this form of tile the ring flange 13 is also shown integral with the tile but could equally well be formed as a separate part.

I have shown in Figure 4 another modification which is similar to Figure 1 in that it does 60 not employ a specially formed tile. In this figure the vitreous ring flange is replaced by a metal ring flange 18 which may be plated with nickel or chromium to resist corrosion or it may be enameled to match the tile. The 65 end of the bar is here shown with ridges or

lugs thereon to assist in retaining the bar in the cement.

While the bar has been illustrated in each instance as applied to a tiled wall construction it is to be understood that it is not so limited but may be employed in other connections.

70 It will be noted that a construction has been provided in which no metal need be employed and by which the vitreous bar may be supported in a rigid manner. The ring flange completely closes the cement joint, thus protecting it and hiding it from view and the bead 11 completely closes the opening in the ring flange, preventing entrance of dirt and moisture into the interior of the assembly. The rod is thus rendered extremely easy to clean and no place is provided for the collection of dirt.

75 It is very common in tile construction to employ colored tiles and where such colored tiles are used it is the customary practice to provide white tile fixtures, due to the inconvenience and expense of manufacturing a complete set of fixtures in each color and shade. 80 When so employed the white fixtures are very conspicuous and in many instances mar the appearance of the room. The present bar, however, may be constructed of glass which due to its transparent and translucent nature, 85 transmits and reflects the color of the adjoining tile, blending therewith and presenting a harmonious appearance with whatever color of tile it is used.

90 Obviously, other modifications of the present invention will be apparent to those skilled in the art and I do not desire to be limited to the precise construction shown and described herein.

95 What I claim is:

1. A support for towels and similar objects comprising a bar of vitreous material having its ends arranged at an angle to the body portion and embedded in a wall surface, an annular member surrounding each of the ends of said bar and disposed adjacent said wall surface and a shoulder on said bar engaging said annular member to maintain said member in contact with said wall surface.

100 2. A support for towels and similar objects comprising a bar of vitreous material having its ends arranged at an angle to the body portion and embedded in a wall surface, a separate annular member surrounding each of the ends of said bar and means on said bar for maintaining said member adjacent said wall surface.

105 3. The combination with a tiled wall having a recess therein, of a vitreous bar securely embedded in said recess, a ring flange about said bar covering said recess and means on said bar in contact with said ring flange for maintaining said ring flange in contact with said tiled wall.

110 4. The combination with a tiled wall hav-

ing a recess therein, of a vitreous rod securely cemented in said recess, a separate ring flange about said rod covering said recess and an annular shoulder on said rod for maintaining said ring flange in contact with said

5 tiled wall.

5. A towel bar for tiled wall construction comprising a rod or bar of vitreous material having its ends bent at an angle to the body portion, a tile having a recess therein for the 10 reception of an end of the bar, a member loosely surrounding said bar and abutting against said tile to close said recess, means within the recess for securing the bar therein and means on said bar for maintaining said

15 member in contact with the tile.

6. A towel bar comprising a glass bar having its ends bent normal to the body portion and embedded in a wall surface and secured therein by cement, said embedded end being roughened to retain the same in said cement, 20 means disposed about the bar adjacent the wall covering said cement and a member on said bar engaging said means to retain the same in contact with the wall surface.

25 7. A towel bar comprising a glass bar having its ends bent normal to the body portion and embedded in a wall surface and secured therein by cement, protuberances on said embedded end to retain the same in said cement, 30 a vitreous ring flange about the bar adjacent the wall for covering said cement and an enlargement on said bar abutting against and entirely closing the opening in said ring flange.

In testimony whereof, I have hereunto subscribed my name this 3rd day of August, 1926.

EUSTACHIUS W. KOERING.
